AUTOMOBILE FENDER

Charles F. Gitschlag, Jr., Detroit, Mich., assignor to Chrysler Corporation, Highland Park, Mich., a corporation of Delaware

Application March 2, 1955, Serial No. 34,827

Term of patent 7 years

(Cl. D14—6)

Fig. 1 is a top plan view of an automobile fender showing my new design;

Fig. 2 is a side elevational view thereof;

Fig. 3 is a front elevational view thereof;

Figs. 4 and 5 are sectional views taken on the lines 4—4 and 5—5, respectively, of Fig. 2; and

Figs. 6 and 7 are sectional views taken on the lines 6—6 and 7—7, respectively, of Fig. 3.

The dominant feature of my design resides in the full line portion of the drawing.

I claim:

The ornamental design for an automobile fender, substantially as shown and described.
